(57) **CLAIM**

An ornamental design for a house shaped pastry, as shown and described.

DESCRIPTION

FIG. 1 is a left view of a left side component of a house shaped pastry herein;

FIG. 2 is a perspective view of the left side component of FIG. 1;

FIG. 3 is right view of a right side component of the house shaped pastry herein;

FIG. 4 is a perspective view of the right side component of FIG. 3;

FIG. 5 is a front view of a front side component of the house shaped pastry herein the rear view of the rear component being identical to FIG. 5;

FIG. 6 is a perspective view of the front side component of FIG. 5, the perspective view of the rear component being identical to FIG. 6;

FIG. 7 is a view of a right side top component of the house shaped pastry herein;

FIG. 8 is a perspective view of the right side top component of FIG. 7;

FIG. 9 is a view of a secondary right side top component of the house shaped pastry herein;

FIG. 10 is a perspective view of the secondary right side top component of FIG. 9;

FIG. 11 is a view of a left side top component of the house shaped pastry herein;

FIG. 12 is a perspective view of the left side top component of FIG. 11;

FIG. 13 is a right side view of the house shaped pastry of FIG. 17;

FIG. 14 is a left side view of the house shaped pastry of FIG. 18;

FIG. 15 is a front view of the assembled house shaped pastry of FIG. 17;

FIG. 16 is a top view of the assembled house shaped pastry of FIG. 17;

FIG. 17 is a front, top and right side perspective view of the assembled house shaped pastry; and,

FIG. 18 is a rear, top and left side perspective view of the assembled house shaped pastry.

The broken lines shown in FIGS. 3-6, 13, 15, 17 and 18 illustrate portions of the house shape pastry that form no part of the claimed design.
